JOHN D. IHLDER, OF NEW YORK, N. Y., ASSIGNOR TO OTIS ELEVATOR COMPANY, OF JERSEY CITY, NEW JERSEY, A CORPORATION OF NEW JERSEY.

MOTOR-CONTROLLING SYSTEM.

No. 872,349.

Specification of Letters Patent.

Patented Dec. 3, 1907.

Application filed July 28, 1905. Serial No. 271,585.

To all whom it may concern:

Be it known that I, JOHN D. IHLDER, a citizen of the United States, residing at New York city, in the county of New York and 5 State of New York, have invented a new and useful Improvement in Motor-Controlling Systems, of which the following is a specification.

My invention relates to improvements in 10 motor-controlling systems and is adapted to the operation of electric motors in general but is particularly applicable to those used for hoisting purposes in which the motor is frequently started, stopped and reversed.

15 One of the objects of my invention is the provision of a simple and efficient means for preventing current from passing through both of the motor-reversing means should the circuits to the latter become deranged.

20 Another object of my invention is to automatically stop the motor should the circuits be thus deranged.

A further object of my invention is the 25 provision of a simplified construction for preventing excessive speed of the motor.

Other objects of this invention will appear hereinafter.

My invention consists of the apparatus, 30 circuits and connections hereinafter described, the novel combinations being pointed out in the claims.

The accompanying drawing illustrates my invention as applied to an electric hoisting or elevator system including a car C having 35 a manually operable switch O which is used to control the starting, stopping and reversing of the hoisting motor M.

R and R' are the reversing switches which 40 determine the direction of rotation of the motor-armature.

T designates a number of small switches which are for the purpose of automatically slowing down and finally stopping the car at the upper and lower limits of its travel.

45 D and E are magnetic switches which operate to prevent the motor M from reaching too high a speed.

H is a magnetic switch which operates in conjunction with the "load magnet" L to 50 automatically slow down the elevator at the desired landing to an amount proportional to the load.

S and F are magnetic switches used to produce speed changes.

A designates what I call an accelerating 55 magnet which operates contacts controlling the insertion and cutting out of the starting resistance and series field 51.

P designates a potential or safety switch which serves to connect the source of current supply + and - to the system.

B is a safety magnetic switch and its duty is to prevent both of the magnet coils of the reversing switches R and R' from receiving current at the same time as this would tend 65 to destroy their proper operation.

The potential switch P is shown in its closed position, that is, the supply mains + and - are connected to the wires 2 and 3, respectively. The switch is held in this 70 position against the action of a spring by the magnet coil 1 which receives current at the full line potential being connected through the normally closed contacts of the magnet B to the positive and negative mains. 75

The manually operable switch O comprises a contact segment 12 adapted to be moved into engagement with the fixed contacts 4, 5, 6 and 7 when moved by the handle 13 in one direction and into engagement with the contacts 8, 9, 10 and 11 when moved in the opposite direction.

A wire 14 connects the segment 12 through one or the other of the contacts 7 and 11, depending on which way the segment is moved, 85 to the potential switch 15 which is connected to the - supply main by one of the arms of switch P.

In order to understand the operation of my system, let the handle 13 of switch O be 90 moved to the left until the segment 12 engages the fixed contact 4. This will connect the negative wire 14 to the lower terminal of the magnet H through the contacts of stop-motion switch T which are connected by the 95 bridging piece 16, the other terminal of magnet H being connected by the wire 17 to the movable contacts 18, 19, 20 and 21 of the reversing switches, a circuit to the positive wire 2 being open at these reversing switch 100 contacts. The segment 12 of switch O is now moved until it engages the fixed contact 5 when a circuit will be established from the negative wire 14 by the bridging piece 22 of switch T to the magnet coil 23 of reversing 105 switch R, the other terminal of this coil 23 being connected through the coil 24 of switch B, and by wire 79, to the positive main.

Thus it will be seen that a circuit has been established from the positive to the negative main through the magnet 23 and coil 24 of the safety switch B.

5. The motor starting or reversing switches R and R' each comprises a magnetic core or plunger to which are fastened insulated pieces carrying contacts such as 18, 19, 20, etc. In the path of these movable contacts 10 are fixed contacts such as 34, 36 and 37' which are adapted to be engaged by them. The coil 23 of switch R, when energized, tends to raise its core to which are fastened the contacts 31, 32, 18 and 19 in an upward 15 direction causing the contacts 18 and 19 to engage the fixed contacts directly above, that is, 34, 35, and 36, respectively. The movable contacts 31 and 32 will at the same time be moved away from the fixed contacts 30 and 33, respectively. The coil 29, however, tends when excited to pull the core and its contacts in a downward direction. The switches R and R' have a rocker arm which is fastened by a pin on each core of the 25 respective switches and operates to prevent both switches being in their extreme upward or downward positions at the same time. This interlocking device may be as shown on the drawing, or it may be such as shown in 30 the Patent No. 704,336, granted me on July 8, 1902, wherein a pair of reversing switches is shown and described whose construction is similar to the switches R and R' of the present case.
35. As shown hereinbefore, when the segment 12 of the switch O is moved so as to energize the contact 5, a circuit is established through the reversing switch coil 23 and the coil 24 of magnet switch B. The magnet 23 will cause 40 the contact 18 to engage the fixed contacts 34 and 35, and also the contact 19 to engage the contact 36 and by means of the rocker arm or interlocking device between the switches R and R', the contacts 39 and 40 45 will engage the fixed contacts 41 and 42, respectively.

The magnetic switch B, it will be noticed, has two coils 24 and 43. Each of these coils is in series with one of the coils 23 and 27 of 50 the reversing switches R and R', respectively. The coils 24 and 43 are so wound that when one coil alone is energized it has not sufficient strength to cause the contacts 69 of switch B to become disconnected. 55 Should, however, both coils 24 and 43 receive current at the same time the magnet coils 23 and 27 of the switches R and R' would also receive current and make the operation of the reversing switches very uncertain. The 60 coils 24 and 43 are wound cumulatively, that is, one assists the other when both are energized, and when co-acting with each other they have sufficient strength to separate the contacts 69. Since these contacts include a 65 circuit through the wires 80, 81, to the hold-

ing coil of the potential switch P, their becoming separated will cause coil 1 to be de-energized, thereby causing the potential switch arms to drop, severing all connection between the motor controlling system and 70 the source of current supply. The circuit to the brake magnet 52 is broken at the contact 15, thus causing the brake to be applied to stop the motor and hoisting machinery operated thereby.

When the potential switch magnet 1 becomes deenergized, the contacts 66 will be closed by the dropping of the switch arm completing a circuit through the extra field 54 and a small portion of the load resistance 80 55 which is in series therewith. The circuit thus formed is a local circuit including the armature and may be traced from the brush 37 through contacts 41 and 39, wire 44, armature resistance 45, wire 68, contacts 66, 85 wire 67, that portion of the load resistance which is shown at the extreme left in the drawing, continuing through the extra-field 54, wire 56, wire 17, contacts 40 and 42, holding coil 28, to the armature brush 38. 90 A dynamic braking effect is thus produced to cause the motor to speedily come to rest.

When the coil 23 of reversing switch R is energized, the contact 18 engages contacts 34, 35, and the contact 19 engages the contact 36. Substantially at the same time the contacts 39 and 40 engage the contacts 41 and 42, respectively. A circuit is thus closed to the magnet H through the wire 2, contacts 34, 18, and wires 17 and 82. The 100 magnet H is therefore energized and causes its contacts to separate, thus preventing the load magnet L from receiving any current. When the switch R is operated, a circuit is closed also to the magnet 28 from the positive main through the contacts 34, 18, wire 17, and contacts 40, 42. The magnet 28 when energized exerts a downward pull on the core of the reversing switch magnet 27, insuring intimate contact between the contacts 39, 41 and 40, 42, respectively. The 110 circuit through the magnet 28 continues to the brush 38, through armature M, brush 37, contacts 39, 41, and wire 44 to the starting resistances 45, 46, 47, 48, 49, and 50, series 115 field 51, to the negative or - wire 3. The brake will also be raised out of engagement, being connected by contact 35 with the positive line, and to the negative line by wire 14. The motor is now free to start, current to the 120 armature being limited, however, by the starting resistance 45, 46, etc. The series field 51 will also receive current. The shunt field designated by 53 being connected to wire 17 on one side and wire 3 on the other 125 will be energized to its full strength receiving current at full line potential.

The slow-speed magnet S being connected in shunt to a circuit comprising the motor-armature and the resistance 45 will not be 130

energized sufficiently to close its contacts 70 since the difference of potential across the terminals to which it is connected is at the moment of starting very low. As the motor 5 accelerates to slow speed, resulting in a gradually increasing counter-electro-motive force, the magnet S is finally energized to the point where it will operate to close its contacts 70 which will result in connecting the extra 10 field 54 having the load resistance 55 in series with it across the motor armature. One terminal of the extra field 54 is connected to wire 17 and so on to the armature brush 38 and the right-hand end of the resistance 55 15 is connected by wires 56 and 44 which as before shown is connected to the armature brush 37. The extra field will now receive current of an amount depending upon the counter-electro-motive force of the revolving 20 armature and therefore its speed. The next operation of the system is to move the lever 13 of switch O to its extreme left-hand position causing the segment 12 to engage the contact 6. Now contact 6 is connected by 25 the bridging piece 61 of switch T to the wire 62 and by means of the normally closed contacts 76 of magnet switch D to wire 63, the latter being connected to one terminal of the coil of fast-speed magnet F whose other 30 terminal is connected by wire 17 to the positive main. The fast speed magnet F is therefore connected across the power mains and will at once operate to close the contacts 64 and substantially at the same time to 35 open the contacts 65. This will be conducive to two results: first, the separating of contacts 65 will open the circuit to the coil of slow speed magnet S causing it to separate its contacts and thus interrupt the circuit 40 supplying the extra field by wire 44; second, the closing of the contacts 64 will short-circuit the starting resistance 45. The field strength of the motor having been weakened by opening the circuit of the extra field 54 45 the motor will revolve at a faster speed. The resistance 45 having been short-circuited by the magnet switch F the potential across the terminals of the accelerating magnet A, which are practically at this time across the 50 motor armature will have risen to a value sufficient to energize the magnet A. This magnet A has one terminal connected to the wire 17 which is at the same potential as the motor-brush 38, being connected to it. Its 55 other terminal is connected through the contacts 58 and 59 by wire 57 to a point on the starting resistance 46. This magnet then is shunted across a circuit comprising the motor armature and the starting resistance 45 and 60 a portion of resistance 46.

As the motor accelerates from rest the potential will rise in the coil of magnet A which will result in operating the movable contacts of magnet A in succession in a well known 65 way to cut out or short-circuit the starting

resistances. The magnet A as shown controls seven movable contacts shown directly beneath it, and the first five operate to cut out resistance only. The sixth places the resistance 52 in parallel with the series field 70 51, and the seventh and last contact short-circuits this resistance as well as the series field. The motor now runs at its normal full speed as a shunt machine having its armature connected across the power mains and 75 its shunt field alone excited.

The safety magnet switches D and E are connected in parallel to each other and in shunt to the motor armature. Should the motor for any reason run at a higher speed 80 than normal, the voltage would tend to rise, producing a corresponding rise in voltage across the terminals of the safety magnets D and E. Now the magnet D is so set or adjusted that upon a rise of potential above that of normal conditions it will be excited sufficiently to open its contacts 76 to interrupt a circuit supplying the fast speed magnet F, by way of wires 62 and 63, causing the switch F to become deenergized and drop its plunger 85 which would result in establishing a circuit to slow speed switch S and cause the latter to close a circuit to the extra field 54 through the load resistance 55. At about the same time, the fast speed magnet F re-inserts the 90 resistance 45 into the armature circuit. The increase in armature resistance and in field magnetism thus produced will cause the motor to at once slow down when the magnet D will again permit the contacts 76 to engage 100 with each other. The safety magnet E is set to operate at a somewhat higher voltage than that required to operate magnet D so that should the potential across the motor-armature reach a value high enough to operate 105 magnet E, it will open its contacts 77, which maintain a circuit supplying the potential switch magnet 1 and by so doing allow the magnet 1 to become deenergized and interrupt the main line circuit and also to open 110 the circuit supplying the brake magnet 52. The operation of the safety magnet E therefore breaks the current-supply to the motor and effects the application of the brake, while the motor and circuits act as a dynamic 115 brake until the motor has come to rest.

In order to show the normal method of stopping, such as making a landing, let it be supposed that the motor has been brought to full speed, the contact segment 12 of switch 120 O being in engagement with four fixed contacts 7, 4, 5 and 6. The first step is to move the lever 13 until the contact segment 12 moves out of engagement with the contact 6. This will open the circuit by wire 62 to the switch 125 F, causing the same to operate to insert the resistance 45 in the armature circuit and to energize the magnet of switch S, thereby energizing the extra field 54 in a manner which was clearly pointed out in connection with 130

the operation of the safety-magnet D. The motor now runs at a reduced speed. The segment 12 of switch C is next disengaged from contact 5. This breaks the circuit to the magnet coil 23 of the reversing switch R causing it to drop, and as before stop the motor. Should, however, the handle of the switch O be rapidly brought from its extreme or fast speed position to its center or 5 "off" position, a circuit through wire 83 to the magnet H would in this case be broken at the switch contact 4. The magnet H would therefore be deenergized and on closing its contact establish a circuit to the load 10 magnet L, the latter being thereby connected across the terminals or brushes of the motor armature. The result of this would be to energize the magnet L to close more or less of its contacts in a well known way and thereby 15 short-circuit or cut out of circuit more or less of the load resistance 55 depending upon the voltage across the armature brushes which is proportional to the speed of the motor. The contacts controlled by the load magnet, of 20 which five are shown, are similar in construction with the exception of the second one 60 which is fastened to, but insulated from, a small contact 58 which contact is in engagement with a small fixed contact 59 25 when not raised out of contact by the operation of the load magnet L. Should the motor be generating sufficient counter-electromotive force during the period required to stop, the load magnet L, having been connected in circuit by the operation of the magnet switch H, will raise the contact 60 causing the circuit which energized the accelerating magnet A to become broken through the wire 57. The accelerating magnet will therefore drop its contacts. This would prevent 30 the operator from accelerating to full speed once more (since the circuit to the accelerating magnet A is broken) until the contacts 58 and 59 have again been brought into contact 35 which would insure the starting resistance together with the series field being again included in the armature circuit, and preventing current at the full line potential being thrown on the motor until the extra field 40 has been weakened by having the load resistance connected in series with it.

The automatic limit switch T comprises two sets of switches, each set having three switches. Each switch is indicated or 45 shown on the drawing as comprising two small contacts which are bridged by a metallic bridging piece such as 16 and 61. The upper set of three switches are operated by some part of the hoisting machinery, one set 50 of three operating as the car approaches the upper limit of its travel; the other set of three switches being similarly operated as the car approaches the lower limit of its travel. The switches in each set are 55 constructed so as to operate successively, to pro-

duce an automatic stop similar to that produced by the switch O when the latter is brought from a full speed position to a stop or "off" position by virtue of the connections to the switch O being led through the 70 same switches. Therefore, should the operator leave the switch O in any of the running positions, the automatic switch T would at the limit of travel stop the machine.

The operation of the reversing switch R' 75 is brought about when it is desired to run the motor in a reverse direction, by moving the handle 13 of the switch O in a right-handed direction causing the contacts 8, 9 and 10 to become energized. In this case the circuits 80 through the switch C pass through the lower set of switches comprising the automatic switch T. The operations of the units are similar to the previously described operation. A circuit to magnet coil 27 passes 85 through the coil 43 of magnet B while the circuit to the motor-armature passes through coil 29 of the reversing switch R. The current passes through the motor-armature in a reverse direction to what it did in the former 90 case, producing a reverse rotation of the motor. The brake magnet is now fed with current through the contact 37' instead of contact 35 as before.

In reviewing the operation of the system 95 as disclosed, it will be seen that the excessive speed magnet switches D and E provide for and effectually prevent any undue increase in motor speed which so frequently is conducive to disastrous results. Also the safety 100 magnet switch B with its double magnet coil which operates at once to stop the machine should the reversing switch coils get grounded on one another, or should both of the magnet coils which operate the reversing switches 105 R and R' receive current at the same time, from whatever cause, the machine is at once brought to rest.

Without limiting myself to the precise construction of details or arrangement of parts 110 herein shown and described, but reserving the right to vary the same within the spirit and scope of my invention, what I claim and desire to have protected by Letters Patent is:

1. The combination with a pair of reversing switches, of electromagnets for actuating the same, an additional electromagnet, and means controlled by said additional electromagnet for preventing the operation of both 120 of said switches at the same time.

2. The combination with a pair of reversing switches, of electromagnets for operating the same, an additional electromagnet having coils in series with the aforesaid electromagnets, and means controlled by said additional electromagnet for insuring the operation of only one of said switches at a time.

3. The combination with a plurality of switches, of electromagnets for operating 130

- said switches, an additional electromagnet having coils wound to assist one another, said coils being in series with the first-named electromagnets, and means operated upon 5 the energization of more than one coil of said additional electromagnet for preventing the operation of more than one switch at a time.
4. The combination with a motor, of electric motor-controlling means, reversing 10 switches, magnets for operating said switches, a circuit-breaker, and means for operating said circuit-breaker to cause the stopping of the motor upon both of said magnets receiving current at the same time.
- 15 5. The combination with a motor, of controlling means therefor, circuits and connections for said motor and motor-controlling means, reversing switches, magnets for operating said switches, a potential switch in the 20 main line circuit, and means co-acting with said motor-controlling means and magnets for operating said potential switch to interrupt the main line circuit upon both of said magnets receiving current at the same time.
- 25 6. The combination with a motor, of reversing switches therefor, electromagnets for operating said switches, a safety magnet having coils respectively in series with the first-named electromagnets, and means controlled by said safety magnet for interrupting the circuit to the motor upon energization of both coils of said safety magnet.
- 30 7. The combination with a motor, of motor-controlling-means comprising reversing 35 switches, electromagnets for operating said switches, a safety magnet having coils respectively in series with the aforesaid electromagnets, and means for interrupting the circuit to said motor-controlling-means operated by said safety magnet upon the energization of both of its coils.
- 35 8. In an elevator, the combination with a car and its motor, of motor-controlling-means comprising reversing switches and 40 electromagnets for operating same, a safety magnet with its coils wound cumulatively and respectively in series with the aforesaid electromagnets, and means controlled by said safety magnet for bringing the car to a 45 gradual stop upon energization of both the coils of said safety magnet.
- 45 9. In an elevator, the combination with a car and its motor, of reversing switches for 50 said motor, electromagnets for operating said reversing switches, a safety magnet having coils cumulatively wound and respectively in series with the aforesaid electromagnets, a potential switch for the main line circuit, means for automatically reducing the 55 speed of the car before stopping and varying such reduction of speed in accordance with the load, and means operated by said safety magnet upon current passing through both the first-named magnets and the coils of said
- safety magnet for interrupting the circuit to 60 said potential switch to cause the same to close the circuit of said automatic slowing-down means.
10. The combination with a motor, of an electro-magnet in shunt thereto, an extra field circuit, and means controlled by said electro-magnet for introducing said extra field circuit to retard the speed of the motor upon the same exceeding a predetermined limit. 70
11. The combination with a motor, of an electromagnet in shunt thereto, an electro-magnetic potential switch, and means controlled by the aforesaid electromagnet for effecting the opening of said switch to interrupt the circuit to the motor upon the same attaining an excessive speed. 75
12. The combination with a motor, of an electromagnet in circuit therewith, an electro-magnetic potential switch for controlling 80 the motor, and means controlled by said electromagnet for interrupting the circuit to said motor-controlling-means upon the motor attaining excessive speed. 85
13. The combination with a motor, of an electromagnet in circuit therewith, reversing switches for said motor, and means controlled by said electromagnet for interrupting the circuit to said reversing switches upon the motor attaining excessive speed. 90
14. The combination with a motor, of an electromagnet in circuit therewith, reversing switches for the motor, and means controlled by said electromagnet for temporarily interrupting the circuit of an operated reversing switch upon the motor exceeding a predetermined speed. 100
15. The combination with a motor, of an electromagnet in circuit therewith, reversing switches for the motor, electromagnets for 105 operating said reversing switches, and means controlled by said electromagnet for interrupting the circuit to said second-named electromagnets upon the motor-speed exceeding a predetermined value. 110
16. The combination with a motor, of starting resistance therefor, a magnet in circuit with the motor, an accelerating magnet for short-circuiting all but a portion of said resistance, an additional magnet for short-circuiting the said remaining portion of the resistance, and means controlled by said first-named magnet for interrupting the circuit to said additional magnet to effect a reinsertion of said portion of the resistance 115 upon the motor attaining an excessive speed. 120
